UNITED STATES PATENT OFFICE.

WILLIAM SCOTT CAMPBELL, OF PHILADELPHIA, PENNSYLVANIA, ASSIGNOR TO LINK-BELT COMPANY, OF CHICAGO, ILLINOIS, A CORPORATION OF ILLINOIS.

MEANS FOR MANIPULATING TELESCOPIC CHUTES.

Application filed February 8, 1921. Serial No. 443,386.

To all whom it may concern:

Be it known that I, WILLIAM S. CAMPBELL, a citizen of the United States, residing in Philadelphia, Pennsylvania, have invented certain Improvements in Means for Manipulating Telescopic Chutes, of which the following is a specification.

My invention relates to certain improvements in means for operating telescopic chutes, which are used for the purpose of loading material, such as coal and the like, in such a manner that the amount of breakage will be reduced to a minimum. To accomplish this, the material is discharged into the top of the telescopic chute while the chute is retracted. When this retracted chute is filled with material, the chute is gradually lengthened and lowered to the desired point, where the material can be discharged. While this operation is going on, the material is fed into the top of the chute, keeping it filled at all times.

One object of my invention is to provide means for operating the telescopic chute while it is loaded with material.

A further object of the invention is to overcome the friction to a certain extent between the chute walls and the material while the telescoping operation is taking place.

In the accompanying drawings:

Fig. 1 is a perspective view, showing my improved telescopic chute and the boom to which it is attached;

Fig. 2 is a perspective view, showing the reeving of the ropes; and

Fig. 3 is a side view of the chute.

1 is the boom having side members 2 and a cross head 3. This boom is pivoted at 4 to any suitable support. 5 is the boom operating mechanism, which allows the boom to be moved on its pivot. This mechanism forms no part of the present invention.

6 is the telescopic chute, which consists of a number of sections 7 arranged so that one section will telescope within another. The bottom section is secured to a casing 8 which, in the present instance, is an endless discharge belt 9 driven by any suitable motor carried on the casing 8 so as to discharge material through the opening 10 in the casing as it is fed by gravity through the telescopic chute. Material is fed to the upper end of the telescopic chute through a chute 37, Fig. 3. The upper section of

the chute is connected by links 11 to a supporting frame 12. Secured to the upper section of the chute is a frame 13.

14 is a frame attached to the lower section of the chute. The upper end of the chute is suspended from a holding line 15 and the rope of this line passes from the drum 16 of a holding engine around a sheave 17, over a sheave 18 mounted on the cross head 3 of the boom, down to and around a sheave 19 on a shaft 20, then up and over a sheave 21 on an equalizing frame, or bridle 22, then around a second sheave 19^a, returning over a sheave 18^a and around a wheel 17^a to the second holding drum 16^a. When the drums 16, 16^a are turned, the chute can be raised or lowered.

The means for telescoping the chute is as follows:

23 is one of the telescoping drums, from which passes a rope 24, forming the telescopic line. The rope first passes around a wheel 25, then over a sheave 26 on the cross head 3, down to a sheave 27 on the lower frame 14, then up and around a sheave 28 on the frame 13 at the upper end of the chute, then down to a sheave 29 on the lower frame 14, and up to a guide wheel 30 at one side of the bridle 22, then to a wheel 31 on the opposite side of the bridle down to a sheave 32 on the lower frame, up to the sheave 33 on the frame 13, down again to a sheave 34 on the lower frame, then over a sheave 35 on the cross head 3 and around a guide wheel 36 to a drum 23^a. On turning the drums 23 and 23^a, the telescopic chute can be contracted or extended.

The ropes are so reeved to the upper and lower sections of the chute that the chute can be contracted while it is full of flowing material, the power exerted overcoming the friction between the chute walls and the material while the chute is being contracted.

When it is desired to raise the chute bodily, both sets of drums are operated, which causes the frame 12 to move towards the cross head 3 of the boom, as well as the lower frame 14 and the frame 13. This action prevents the rope 24 becoming slack.

By this arrangement, the upper end of the chute can be held in a fixed relation to the feeding chute, or hopper, while the body of the telescopic chute can be lengthened or shortened, as desired. Consequently, the chute can be kept filled with coal, or other

material, at all times, and, as the material is discharged at the bottom of the chute, fresh material flows into the top of the chute, so that the material flowing through 5 the chute will be carried to the discharge point with practically no breakage.

It will be understood that the reeving of the ropes may be modified without departing from the main feature of the invention, 10 as, in some instances, a single reeving may only be necessary, while in other cases additional reeving may be required.

While I have shown one means attached to the upper and lower ends of the telescopic 15 chute for lengthening or shortening it, equivalent means may be used without departing from the spirit of the invention.

I claim:

1. The combination of a telescopic chute; 20 a frame at the bottom of the chute; a frame from which the top of the chute is suspended; a second frame at the top of the chute; two ropes, one rope connecting the frame, which is attached to the upper end 25 of the chute, to the supporting structure; means for operating the rope, the other rope

extending to the bottom frame and the mid frame; and means for operating the latter rope to contract or expand the chute.

2. The combination of a telescopic chute; 30 a boom from which the chute is suspended; a frame at the base of the chute; a frame attached to the upper end of the chute; an intermediate frame, also attached to the upper end of the chute; rope sheaves on the 35 frames; two ropes, one rope passing around the sheaves on the supporting structure and around the supporting frame at the upper end of the chute, the other rope passing 40 around sheaves on the supporting structure 40 and down to and around sheaves on the lower frame, then up and around the sheaves on the intermediate frame and down to the lower frame and up over a sheave on the supporting structure so that, when the last 45 mentioned rope is manipulated, the chute can be increased or diminished in length and, when both ropes are manipulated, the chute can be raised bodily towards the support.

WILLIAM SCOTT CAMPBELL.
